U.S. Cl. D48—20

FIG. 1

FIG. 2

FIG. 3

FIG. 5

FIG. 4

FIGURE 1 is a general perspective view of the surgical lamp or the like;

FIGURE 2 is an enlarged bottom plan view of the surgical lamp or the like shown in FIGURE 1;

FIGURE 3 is a top plan view of the surgical lamp or the like shown in FIGURE 1;

FIGURE 4 is a sectional view taken along line 4-4 of FIGURE 3; and

FIGURE 5 is a cross sectional view taken along line 5-5 of FIGURE 3.

The dominant features of my design reside in those portions shown in full lines on the drawings. The support arm and attachment for the lamp, shown in broken lines in FIG. 1, are omitted in FIGS. 2, 3 and 4 for convenience of illustration.

I claim:

The ornamental design for a surgical lamp or the like, substantially as shown and described.
